ELLIPSE GENERATOR

Paul F. Boehm, Greenwich, Conn.

Application October 18, 1945, Serial No. 623,002

7 Claims. (Cl. 33—39)

1

The present invention refers to instruments or devices for generating elliptic curves. More particularly, the invention is concerned with a device adapted to generate elliptic curves derived from an already existing elliptic master, the size of the elliptic master being different from that of the elliptic curve to be generated, the elliptic proportions, however, of the curve being identical with those of the master.

In the following specification and in the claims the term "elliptic master" means any type of a solid body having an elliptic contour and also any type of an elliptic groove or opening in a solid body.

Moreover, the term "elliptic proportions" means the shape of a particular ellipse, regardless of size, as determined by the projection of a circle on a given plane under one selected angle of projection.

It is one object of this invention to provide a device that is suited to derive from one chosen elliptic master any number of elliptic curves different in size but of the same elliptic proportions as the master, the variation in size being effected by exchanging only one element of the device.

A further object of the invention is the provision of a device of the above type by which an elliptic curve may be generated either by means of a pencil, pen or similar implements as for instance in the art of drawing, or by means of a tool of any kind adapted to engrave, cut or otherwise produce an elliptic shape in a given solid body. In a similar way, the device according to the invention is intended to be used for controlling indirectly the movement of a tool in relation to the work so as to ultimately generate an elliptic curve or shape.

Further objects of the invention will become apparent from the following specification describing, by way of example, some embodiments of the invention with reference to the accompanying drawings.

Figs. 1, 2, 5 illustrate one embodiment of the invention, and in particular Fig. 1 is a top view and Fig. 2 the corresponding lengthwise section of the main structure of the device; Figs. 3 and 4 are vertical cross section and bottom view, respectively, of one of the exchangeable attachments; Fig. 5 is the end view of one element of the said structure.

Fig. 6 is a vertical cross section of an alternative type of the attachment.

Figs. 7 and 8 are a vertical cross section and a bottom view, respectively, of another alternative type of attachment. Figs. 9 and 10 are top

2

view and elevation, partly in section, of another embodiment of the invention. Figs. 11 and 12 illustrate the same attachment as shown by Figs. 3 and 4, as applied to the device illustrated by Figs. 9 and 10.

Fig. 13 is a perspective view of still another embodiment of the invention.

Fig. 14 is a diagram intended to explain the geometrical principles governing the performance of a device according to the invention.

Referring first to Fig. 14, it may be supposed that a circle 10 is given, having a diameter A. A number of small circles 11 may be drawn in such a way that they contact the periphery of circle 10 from the inside. Then the centers of all the small circles 11 will be located on a circle 12 which is concentric with circle 10. If the diameter of the circles 11 is B, then the diameter of circle 12 will be A—B.

Let us imagine that the whole system of circles is now projected on a given plane under a certain angle. Then every one of the circles 10, 11 and 12 is converted into a corresponding ellipse. The major axes of these ellipses 10a, 11a and 12a, respectively, are equal to the circle diameters A, B, C, respectively. It is to be understood that C is equal to A—B. The minor axis of the various ellipses is determined in proportion to the major axis by the chosen angle of projection.

Since obviously the small circles 11 may be positioned anywhere along circle 10 without changing the prevailing conditions it may as well be assumed that one circle 11 is moved in contacting position along circle 10 which will cause the center of that circle 11 to generate the circle 12.

All of these conditions are necessarily maintained also in the projection with the only difference that the circles are replaced by ellipses. This means that if a small ellipse 11a having a major axis B is moved along a larger ellipse 10a of identical elliptic proportions and in permanent contact therewith and their major axes being maintained parallel with each other, then the center of ellipse 11a will generate another ellipse 12a which is concentric with ellipse 10a and has the same elliptical proportions, its major axis being C and parallel with that of ellipse 10a.

While in the above example the small circles 11 or ellipses 11a are located and moved inside the main circle 10 or ellipse 10a in order to generate a circle 12 or ellipse 12a, respectively, smaller than the main circle or ellipse, it will be readily understood that in the same way a

circle or ellipse larger than the main circle or ellipse may be generated by moving the small circles or ellipses along the outside of the main circle or ellipse.

The devices according to the present invention are based on the geometrical principles just explained above.

The common feature of all the embodiments of the present invention is the fact that they comprise means adapted to guide a tracing or guided element of given elliptical shape along a given elliptic master or guiding element in such a way that the major axes of the tracing element and of the master are maintained parallel with each other. By using alternatively tracing elements of different size a practically unlimited number of ellipses concentric with each other and the master, of same elliptic proportions but differing in size may be produced from one particular master. The difference in size, i. e. the difference between the major axis of the master and that of the generated ellipse will always be equal to the major axis of the elliptic tracing element provided the point of the scribing or cutting device is located within the center line of, and perpendicular to the plane of, the elliptic contour of the tracing element.

Referring to Figs. 1 to 5, the device comprises a base 20 of rectangular shape which in this case is provided with an undercut 21 and two engaging pins 22 intended to serve as means for attaching the base 20 to a plate or stencil of flat stock which contains one or more elliptic openings serving as masters. A stencil or master of this type is not shown in connection with the first two examples as it does not necessarily form part of the device proper. However, reference may be had in this connection to Fig. 13 which illustrates a stencil or master plate. It will be understood that suitable holes may be provided in the stencil plate adapted to be engaged by the pins 22 so as to hold the base 20 in a predetermined position in relation to the ellipse openings in the plate.

The base 20 is provided, along a center line parallel with the undercut edge, with two solid pivots 23. One swivelling slide block 24 is mounted on each of the pivots 23 and held in position by a nut 25 screwed on the end of the pivot. The blocks 24 are each provided with a bore 26 at right angles to the holes engaging the pivots. Preferably the blocks 24 are split at 27 and provided with adjustment screws 28 permitting to slightly adjust the size of the bore 26.

A parallelogram frame or linkage is composed of two slide bars 29 of equal length and of a diameter permitting them to slide smoothly through the bores 26 of the blocks 24; the rest of the linkage is constituted by flat end link 30 and a similar flat front link 31, both links pivotally connected at either end with the corresponding ends of the slide bars 29.

Bearing in mind that the center distance between the two stationary pivots 23 is equal to the distance between the pivotal joints of each of the links 30 and 31, respectively, it will be understood that the parallelogram frame may be moved both lengthwise and, in a swinging movement, sidewise without the front link 31 getting out of alignment parallel with the center line of the pivots 23 or a given line on the master plate attached to base 20.

The front link 31 is provided with means for securing to it a tracing element adapted to be guided along the elliptic contour of an elliptic

master and having itself an elliptic contour adapted to be kept in contact with the master during the tracing operation.

In the present instance the tracing element shown in Figs. 3 and 4 consists of a substantially conical piece 32 that may be clamped to the link 31 by means of a forked bracket 33 and a clamping screw 34 to be threaded into a screw hole 35 of the link 31. A straight shoulder 36 suited to bear against the front edge of link 31 serves to assure a definite position of element 32 with respect to the base 20 and thereby also with respect to a given line contained in the master plate to which base 20 may be attached.

The lower end of element 32 has an elliptical contour as shown at 37. In the present example the major axis of this elliptical contour 37 is parallel with the shoulder 36 and therefore remains parallel with the front edge of base 20 no matter what movements are carried out by the parallelogram frame. Assuming the device is used for drawing ellipses on a sheet of paper on a drawing board and in connection with a flat stencil or template as shown in Fig. 13 having elliptical openings the major axes of which are parallel with base 20 as attached thereto, then the elliptical tip 37 of the tracing element 32 may be guided freely within any one of the elliptic openings of the stencil and in continuous contact with the edge of such opening. During such movement of element 32 the center point of the elliptical tip 37 will generate an ellipse which is of identical elliptical proportions with that of the stencil ellipse provided the elliptical contour 37 meets this condition. The difference in size of the generated ellipse will correspond to the difference established by the major axis of the elliptical contour 37. Assuming the master ellipse in the stencil has a major axis of 2" and the tip 37 has a major axis of $\frac{1}{16}$ " then the generated ellipse will have a major axis of $1\frac{15}{16}$ ".

In order to permit drawing the generated ellipse by means of an ordinary pencil the element 32 is provided with a conical bore 38 suited to accommodate the tip of the pencil and ending with a small opening 39 in the center point of tip 37.

In order to permit drawing or generating ellipses differing from given master ellipses by a variety of differentials, a number of elements 32 having elliptical tips 37 of different sizes may be provided and clamped to the parallelogram frame alternatively.

Fig. 6 illustrates a modified form of a tracing device. The conical piece 32a is again provided with a bracket 33, a shoulder 36 and an elliptical tip 37. However, the inside bore is not conical throughout but provided with a screw 40 having a narrow central bore 41 corresponding in size to the bottom opening 39 so that a thin lead of the type used for mechanical pencils may be inserted and adjusted to project through opening 39.

It will be understood without an illustration that the tracing device may be modified in various ways so as to be adapted to hold other means for producing the generated ellipse on some object or surface, for instance a steel needle for scribing, a lettering pen for drawing an ellipse in ink, or a cutting tool of any suitable kind. Also the tracing element according to this invention may serve as a means for controlling other mechanisms intended to be used for cutting or otherwise producing ellipses or elliptical shapes, for instance a copying or duplicating machine of the pantograph or equivalent type.

There is no necessity of having the major axis of the elliptical tip 37 of the tracing elements parallel with the base 20 or rather with the center line connecting the pivots 23. It is only required to arrange the major axis of tip 37 at the same angle with respect to some part of the parallelogram frame which that particular part maintains during its movements with respect to the major axis of the master ellipse.

Since, as a rule, it will be necessary and desirable to use various tracing elements differing from each other by the size, shape or position of the elliptical contour at the lower tip 37 an advantageous modification of the tracing element may be provided alternatively. This alternative is illustrated by way of example by Figs. 7 and 8. In this instance, eight elliptical tips 42 are arranged evenly spaced, along a circle on a turret head 43. The head 43 is rotatably mounted by means of a pin or screw 44 on a bracket 45 which has a forked end 46 and a straight shoulder 47 similar to the corresponding parts of the elements 32 or 32a and therefore may be attached to link 31 as described above. The pivot pin 44 is angularly disposed with respect to the working surface and the individual tips are so positioned on head 43 that by turning the turret head 43 any one of the elliptical tips 42 may be brought in correct position with regard to the working surface. An extension 48 of bracket 45 contains a lock spring 49 which in appropriate positions of the head 43 will snap into the upper ends of the individual conical bores 50 arranged centrally with the individual tips 42 for accommodating the tip of a pencil used for drawing the generated ellipse.

While the eight different elliptical tips 42 are shown in Fig. 8 having all the same elliptical proportion and the same angular position of their major axes with respect to the pertaining radius of the turret 43, this may be arranged differently as well. For instance, tips 42 with elliptical contours of different shapes and different angular positions may be assembled on one turret.

It is thought that in certain cases the parallelogram frame described above will not be the most efficient or suitable means in guiding the tracing element in proper position during its movement along the master ellipse. In such cases a twin-linkage parallelogram structure as shown in Figs. 9 and 10 may be suitable. In this case the base 20 is the same as in the first example. The pivots 23 are not provided with a nut but with a split retainer ring 25a engaging a corresponding groove. The parallelogram linkage consists mainly of two pairs of connecting rods of identical lengths 51 and 52, respectively, moreover of a center link 53 and a front link 54. The rods 51 are rotatably mounted by means of flat extensions 55 on the pivots 23, and by pins 56 at one side of center link 53. The rods 52 are similarly jointed by pins 57 and 58 respectively to the opposite side of center link 53 and to front link 54, respectively. Again the front link 54 is provided with a clamping screw 34 suited for attaching whatever tracing element is to be used as for instance element 32 shown in Figs. 3 and 4, or element 32a as per Fig. 6 or the turret head illustrated by Figs. 7 and 8. Figs. 11 and 12 are only added to help in understanding Figs. 9 and 10 and do not require further description as they are otherwise identical with Figs. 3 and 4.

It will be understood by those skilled in the art that the parallelogram linkage illustrated by Figs. 9 and 10 permits moving a tracing element

attached to the front link 54 within a considerable range of movement always maintaining a certain angular position of the tracing element with respect to base 20 and thereby with respect to a master plate to which the base may be attached.

Fig. 13 illustrates a still further modification of the present device. In this case the means for maintaining a certain angular position of the tracing element with respect to the base of the device and thereby to the elliptic master being used, consists of a triple-link parallelogram linkage which considerably widens the range of movement of the tracing element.

In general this embodiment of the invention is very similar to those described before. Therefore, the description may be confined to those elements which are different.

The base 20a is of angular shape so that the center line connecting the pivots 23 is at right angles with the center line connecting the pins 22 by means of which base 20a is attached to an ellipse stencil 59. The linkage consists of three pairs of connecting rods 51, 51a and 52, moreover of a link 53a similar to link 53, a front link 54a similar to link 54 and an additional cross link 60. The cross link 60 has two arms 61 extending parallel with link 53a and two arms 62 extending at right angles thereto. One of the arms 62 is offset and the pertaining pivots 64 project in opposite directions so as to permit the two rods 52 to swing at different levels without interfering with the rest of the linkage. Correspondingly, the pivots 65 provided for joining the rods 52 to the front link 54a project also in opposite directions.

It will be understood that the linkage described permits of moving the tracing element 66 very close to the base 20a and, on the other hand, to points comparatively far away from that base.

The tracing element 66 is not attached by a bracket and screw connection but may be inserted through a central hole in link 54a and is held in position by a wire spring 67 which is mounted on link 54a in such a way that it may be brought to snap into a groove 68 cut in the rim of the head 69 of part 66. The groove 68 is not circular but is cut straight in a direction tangential to a circle concentric with the bore 70 accommodating the pencil 71, and at a predetermined angle with respect to the direction of the major axis of the elliptical contour of the tip 72. Obviously the groove 68 may also be cut at various angles so as to form a polygon or part of a polygon around the head 69. Hereby the scanning element 66 can be easily positioned at various angles corresponding to various positions of the ellipse openings possibly occurring in the stencil or master plate 59.

It has been found advantageous to provide means for safeguarding against improper function of the parallelogram linkage that otherwise may happen when the rods 52 are to be swung through the position in which they are one on top of the other. A friction device acting upon the upper rod 52 in the said position will have the effect that the other rod 52 continues its rotary movement slightly ahead of the upper rod whereby the angular position of link 54a with respect to the arms 62 is maintained. In the present instance, the friction device may consist of an extension 73 of spring 67 projecting upward so as to rub against the upper rod 52 in the above mentioned critical moment.

In the above description of certain embodi-

ments of the invention the base of the device has been described always as being directly attached to the ellipse stencil or master plate. This, however, is not a condition that has to be maintained strictly. The device proper may be held independently of the elliptic master provided that their relative position is maintained during its use, for instance by holding either one in fixed position relatively to a common support.

While I have shown and described certain embodiments of my invention I wish it to be understood that I do not want to be limited to the details thereof as many variations and modifications may be found by those skilled in the art without departing from the substance and gist of the invention.

What I claim is:

1. In a device for generating elliptic curves, in combination, an elliptically-shaped guiding element, and elliptically-shaped guided element, the ellipses of said elements being of the same elliptic proportions but differing in size from one another, means mounting said guided element for movement around said guiding element with the elliptically-shaped edges of said elements in contact with each other, and means for maintaining the major axes of said ellipses at all times parallel with respect to each other, whereby the axis of said guided element generates an ellipse concentric to the ellipse of said guiding element.

2. In a device for generating elliptic curves, in combination, an elliptically-shaped guiding element, an elliptically-shaped guided element, the ellipses of said elements being of the same elliptic proportions but differing in size from one another, a parallelogram framework pivotally mounted at one end at a point of fixed relationship with respect to said guiding element, and means mounting said guided element on the free end of said framework with its major axis parallel to the major axis of said guiding element ellipse, said framework maintaining the major axes of said elements parallel at all times.

3. In a device for generating elliptic curves, in combination, a working surface, an elliptically-shaped guiding element, means for holding said guiding element in a fixed position with respect to said working surface, an elliptically-shaped guided element, the ellipses of said elements being of the same elliptic proportions but differing in size from one another, means mounting said guided element for movement around said guiding element with the edges of said ellipses in contact with each other, means for maintaining the major axes of said ellipses at all times parallel with respect to each other, and means positioned at the axis of said guided element for scribing an ellipse on said working surface.

4. In a device for generating elliptic curves, in combination, an elliptically-shaped guiding element, an elliptically-shaped guided element, the ellipses of said elements being of the same elliptic proportions but differing in size from one another, a parallelogram framework pivotally mounted at one end at a point of fixed relationship with respect to said guiding element, said framework

5 maintaining the major axes of said elements parallel at all times and mounting said guided element so that it may be moved around said guiding element with its elliptically-shaped edge in contact with the edge of said guiding element, and means detachably mounting said guided element on said framework, whereby elliptically-shaped guiding elements of different sizes may be mounted on said framework to generate ellipses of different sizes.

10 5. In a device for generating elliptic curves, in combination, an elliptically-shaped guiding element, a turret member having a plurality of elliptically-shaped guided elements mounted thereon, the ellipses of said elements being of the same elliptic proportions but differing in size from one another, a support, means rotatably mounting said turret on said support, whereby said guided elements on said turret may be selectively moved into operative position, means mounting said support to permit movement of the guided element in operative position on said turret in a path around said guiding element with its edge in engagement with the edge of said guiding element, and means for maintaining the major axis of the guided element in operative position parallel to the major axis of said guiding element, whereby the axis of the guided element in operative position generates an ellipse concentric to the ellipse of said guiding element.

20 6. In a device for generating elliptic curves, in combination, a flat plate having an ellipse cut therethrough, an element having an elliptically-shaped edge, the ellipses of the ellipse in said plate and said element being of the same elliptic proportions but differing in size from one another, means mounting said element for movement with its elliptically-shaped edge in contact with the edge of the ellipse cut in said plate, means for maintaining the major axes of said ellipses at all times parallel with respect to each other, and means positioned at the axis of said element for scribing an ellipse concentric to the ellipse in said plate.

25 7. In a device for generating elliptic curves, in combination, an elliptically-shaped guiding element, an elliptically-shaped guided element, the ellipses of said elements being of the same elliptic proportions but differing in size from one another, a parallelogram framework pivotally mounted at one end at a point of fixed relationship with respect to said guiding element, said framework maintaining the major axes of said elements parallel at all times and mounting said guided element so that it may be moved around said guiding element with its elliptically-shaped edge in contact with the edge of said guiding element, and means positioned at the axis of said guided element for scribing an ellipse on a working surface positioned beneath said guided element, the ellipse scribed being concentric to the ellipse of said guiding element.
